UNITED STATES PATENT OFFICE.

THOMAS P. GREENHOW, OF FLINT, MICHIGAN; ANNIE K. GREENHOW ADMINISTRATRIX OF SAID THOMAS P. GREENHOW, DECEASED.

ENGINE CYLINDER AND METHOD OF MAKING SAME.

Application filed May 31, 1922. Serial No. 564,977.

To all whom it may concern:

Be it known that I, THOMAS P. GREENHOW, a citizen of the United States, residing at Flint, in the county of Genesee and State 5 of Michigan, have invented certain new and useful Improvements in Engine Cylinders and Methods of Making Same, of which the following is a specification.

My invention relates to foundry practice 10 and more particularly to cast metal engine cylinders and the method and means for producing them.

The invention pertains to the production 15 of engine cylinders by the use of a chill core, whereby the interior surfaces of the cylinder barrel are rendered of uniform degree of hardness, durable and wear resistant, of increased and uniform density, free from sand or dirt and of approximately the finished 20 size, when taken from the mold, thereby economizing in materials, and the labor and expense of the machine operations as well as improving the wearing quality.

Engine cylinders, particularly those employing an integral water jacket or other 25 projections and other irregularities involving unequal distribution of the mass of metal usually possess comparatively soft interior walls subject to rapid wear and 30 easily scored. Such cylinders frequently lack proper density and possess porous or "spongy" spots, resulting from ununiform crystallization and resulting in pore leaks. These conditions are to a very great extent 35 due to the annealing effect of the surrounding water jacket wall, which is cast integral with the cylinder body, and to enlargements or other unequal distribution of the mass of metal, which tends to retain heat and retard 40 the cooling of the casting, thereby causing it to cool unevenly, resulting in ununiform character of the finished product. Under the usual practice, cylinder barrels vary in hardness throughout their extent being of 45 very much softer character, under the water jacket at the very zone where they should be hard in order to afford long wearing qualities and general durability.

The object of the present invention is to 50 simplify the means and mode of operation of casting cylinder blocks whereby they will not only be cheapened in construction, but will be more efficient in character, of uniform density, and uniform degree of hard- 55 ness.

A further object of the invention is to provide means and methods for producing cylinder cores in close approximation to the finished size and free from sand and dirt, thereby not only economizing metal, but also 60 reducing the machining and finishing operations to a minimum. These results are accomplished by counteracting the annealing effect of the unequal distribution of the metal mass, in the surrounding water 65 jacket and various projections and enlargements by chilling or cooling the cylinder block from the interior, by the means of a chill core, the chilling capacity of which throughout its extent is proportioned 70 conversely to the heat retaining capacity of the casting.

A further object of the invention is to provide an improved form of cylinder chill core, wherein the chills are so positioned 75 and arranged as to compensate for contraction of the casting and to be easily and readily removable from the finished product.

With the above primary and other incidental objects in view as will more fully appear in the specification, the invention consists of the features of construction, the parts and combinations thereof, and the mode of operation or their equivalents as 80 hereinafter described and set forth in the 85 claims.

Referring to the accompanying drawings, wherein is illustrated the preferred, but obviously not necessarily the only mode of carrying out the invention, Fig. 1 is a vertical sectional view of a single engine cylinder embedded in the sand mold with the chill core, hereinafter described, positioned therein, illustrating in a simple manner, the mode of carrying out the present invention. 90 Fig. 2 is a transverse sectional view of the cylinder casting embedded in the mold on line 2-2 of Fig. 1. Fig. 3 is a perspective view of a portion of one half of a core box, 95 with two of the segmental chill plates positioned therein, preparatory to making the cylinder core. Fig. 4 is a perspective view of one of the chill plates, separated from the core.

Like parts are indicated by similar characters of reference throughout the several views.

While engine cylinders are usually cast in multiple wherein the cylinder block contains a plurality of barrels. In the present 110

instance, for illustrative purposes and to simplify the disclosure, only a single cylinder has been shown in the drawings. It is to be understood, however, that the invention is equally applicable to cylinder blocks containing any desired number of barrels. In the drawings, 1 is the engine cylinder casting of which 2 is the water jacket wall. The casting is shown of irregular shape, illustrating the ununiform distribution of the mass of metal and consequent unequal heat retaining capacity. This results in the annealing effect of certain parts of the casting, particularly those parts beneath the surrounding water jacket wall 2, and in close proximity to exterior projections or enlargements of the metal mass. The cylinder casting has been shown in Figs. 1 and 2 as embedded within the usual sand mold 3, and containing a core 4. The coring of castings, by casting the metal around a pre-formed core or interior mold of sand or other friable material, held together by a suitable binder is quite old in the foundry art. Likewise the use of chills, comprising bodies of metal embedded in either the exterior or interior mold are well known. However, there are conditions met with in the casting of hollow cylindrical bodies, such as engine cylinders and the like, and problems encountered for which the customary use of chills affords no solution. It has long been the practice heretofore to cast such cylinder blocks about an ordinary sand core. Such cylinders are often found from thirty-five to sixty per cent softer beneath the surrounding water jacket wall than elsewhere in the cylinder, due to the annealing effect, of the larger mass of metal. This softness occurs throughout the particular portion of the cylinder traversed by the piston which for practical purposes should be the most hard and wear resistant. The unequal distribution of the metal mass further induces lack of density or porosity, in this particular area of the cylinder barrel, where from a practical standpoint the metal should be most dense and without leakage. By embedding segmental chill plates 5 in the periphery of the core 4, the metal forming the interior walls of the cylinder barrel coming in contact with such metal chills is quickly cooled, producing a dense hardened stratum 6, which forms a wear resistant, durable and comparatively smooth interior surface within the bore of the casting. The use of such chill plates also enables the cylinder block to be cast more nearly to the finished dimension of the barrel or core, thereby reducing to minimum the machining and finishing operation. In order to compensate for variations of the mass of metal comprising the casting, the chill plates 5 are varied in thickness throughout their extent. This variation of thickness

may be distributed ununiformly in accordance with the ununiform distribution of metal in the casting. For illustrative purposes, the segmental chill plates 5 have been shown with an offset or shoulder 7 at a medial point whereby the upper portion of the chill plate which will be positioned beneath the walls of the water jacket are of greater thickness than those portions of the plate which project below the level of the jacket. It is to be understood that the chill may be made with a number of these offsets or variations of thickness or it might be tapered uniformly from one end to the other, to compensate for distribution of the metal in the casting. Likewise in the event that the casting contained a considerable body of metal concentrated at one point, the chill might also be of increased thickness over a comparatively small localized area.

The jacketed portion of the cylinder is subjected to sufficiently greater cooling effect to approximately offset the heat retaining characteristics of the unjacketed portion. The real effect is the same whether only the jacketed portion of the cylinder is subjected to the cooling effect and the unjacketed portion not cooled at all, or as an alternative, the jacketed portion is subjected to a considerable degree of cooling effect, and the unjacketed portion to a cooling effect of less degree. By proportioning the cooling effect somewhat in relation to the heat retaining effect of the jacket, a cylinder will not be unduly soft under the jacketed portion.

To compensate for contraction of the casting and to enable the chill plate 5 to be readily removed from the barrel, they are spaced apart a slight distance, leaving intermediate the successive segmental chill plates a narrow ridge 7 of core sand. In practice this spacing of the chill plates 5 one from the other is approximately three sixteenths of an inch. However, this spacing may be varied by locating the chill plates closer or farther apart according to the size of the casting, and the character of the metal, and its factor of shrinkage. In order to locate the chill plate in properly spaced relation for embedding in the core 4, the plates are provided with arcuate marginal notches 8, which engage locating pins 9 in the bottom of the halves of the core box 10. The pins 9 project from the bottom of the core box and receive the notches 8 of the chill plates on opposite sides. These chill plate notches are not semi-circular, but only approximately one third of a complete circle, so that the margins of the plates are separated, the requisite distance, when the notches are fitted to the locating pins 9. These pins by their engagement in the notches also serve to locate the plates in re-

lation to their longitudinal adjustment. For said chill plates, and removing the cast cylinder from the mold and the core and chill plates from the cylinder.

5 The herein described method of producing cast metal engine cylinders and the like consisting in forming a suitable core, embedding in the periphery of such core a plurality of non-interengaging segmental chill plates in separated spaced relation by interposed ridges of core material extending 70 substantially flush with the faces of said chill plate to permit the contraction of the cylinder thereabout, positioning said core in a suitable mold and casting the cylinder from molten metal within said mold and 75 around the core containing said chill plates, and removing the cast cylinder from the mold and the core and chill plates from the cylinder.

10 These holes are then closed by being filled with sand or other green core material.

15 To afford anchorage for the chill plates in the core 4, the interior face of the plates may be formed with a number of depressions or holes as at 11, into which the sand or core material is rammed during the core

20 making operation, thereby securely anchoring the chill plates upon the core body. In addition the core plates are preferably formed with slight draft or taper which 25 further assists in holding the chill plates in place and prevent them from leaving the core while being handled.

From the above description it will be apparent that there is thus provided a device 30 of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language 40 more or less specific as to structural features, it is to be understood that the invention is not limited to the specific details shown, but that the means and construction herein disclosed comprises the preferred 45 form of several modes of putting the invention into effect and the invention is therefore claimed in any of its forms or modifications within the legitimate and valid scope of the appended claims.

50 Having thus described my invention, I claim:

1. The herein described method of producing cast metal engine cylinders and the like consisting in forming a suitable core, 55 embedding in the periphery of such core a plurality of segmental chill plates continuous in longitudinal direction from one end of the area to be chilled to the other, and spaced circumferentially one from the other, 60 and forming longitudinally disposed ridges of core material intermediate said chill plate, and separating them one from the other, positioning said core in a suitable mold and casting the cylinder from molten metal within 65 said mold and around the core containing

- plurality of non-interengaging segmental chill plates embedded in the peripheral surface thereof in spaced relation between which portions of the body of friable material extends in substantially flush relation with the exterior faces of the chill plate.
9. A core for cast metal cylinders comprising a body of friable material, and a plurality of non-interengaging segmental chill plates embedded in the peripheral surface thereof, the chill plates being separated one from another in approximate spaced relation to allow for shrinkage and interposed ridges of core material extending between said plate into substantially flush relation with the exterior faces thereof.
10. A core for cast metal cylinders comprising a body of friable material, and a plurality of segmental chill plates embedded in the peripheral surface thereof, said plates being of varying thickness throughout their length to afford ununiform chilling capacity.

11. As an article of manufacture, a cast metal engine cylinder having a chill hardened interior surface, substantially as specified. 25

12. As an article of manufacture, a cast metal engine cylinder having a surrounding water jacket, the interior of the cylinder being chill hardened to counteract the annealing effect of the surrounding water jacket. 30

13. A chill plate for engine cylinder cores, comprising a segmental arcuate plate of ununiform thickness throughout its length, 35 said plate having locating notches in its marginal edge.

In testimony whereof, I have hereunto set my hand this 22nd day of May, A. D. 1922.

THOMAS P. GREENHOW.

Witnesses:

LEO M. CHURCH,
CARRIE L. HOWARD.
